UNITED STATES PATENT OFFICE.

HERMAN METZ AND EDWARD J. BOWLES, OF CLINTON, ILLINOIS.

SHEET-METAL-BEADING MACHINE.

1,039,776.

Specification of Letters Patent.

Patented Oct. 1, 1912.

Application filed August 11, 1910. Serial No. 576,766.

To all whom it may concern:

Be it known that we, HERMAN METZ and EDWARD J. BOWLES, citizens of the United States, residing at Clinton, DeWitt county, Illinois, have invented certain new and useful Improvements in Sheet-Metal-Beading Machines; and we do hereby declare the following to be a full, clear, and exact description of the invention, such as will enable others skilled in the art to which it appertains to make and use the same.

This invention relates to certain improvements in machines for beading or turning the edges of sheet metal; and the objects and nature of our invention will be readily understood by those skilled in the art in the light of the following explanation of the accompanying drawings illustrating what we now consider our preferred embodiment from other formations and arrangements within the spirit and scope of our invention.

An object of the invention is to provide certain improvements in beading machines whereby an efficient and durable apparatus will be produced capable of operating on both light and heavy sheet metals.

A further object of the invention is to provide certain improvements in formation and arrangement of parts whereby a highly efficient and improved beading machine will be produced.

The invention consists in certain novel features in construction and in combinations and arrangements of parts as more fully and particularly described and pointed out hereinafter.

Referring to the accompanying drawings;—Fig. 1, is a top plan view of the machine. Fig. 2, is a top plan view on an enlarged scale of one end portion of the machine shown in Fig. 1. Fig. 3, is an end view of the machine with the beader rod or mandrel removed. Fig. 4, is a detail plan view of a portion of the beader rod. Fig. 5, is a sectional view in the plane of the line 5—5, Fig. 2.

In the drawings, 1, is the horizontally disposed longitudinal base plate or bed of the machine at the rear portions of its ends having vertically disposed supports 2, forming journal boxes for the operating shaft 3, arranged longitudinally of and above the top face of the rear portion of the bed and having pinions 30, fixed on the end portions thereof and handles 31, for rotating said shaft. The two end crank handles 31, are

usually arranged projecting radially in opposite directions from the shaft, although we do not wish to so limit our invention. At its front longitudinal edge the bed 1, is provided with a vertical portion 10, rising therefrom and rigid therewith and arranged longitudinally throughout the length thereof and forming the fixed or stationary member of the die or bead forming trough or cylinder. The opposite or coöperating die member or section is formed by a longitudinal bar 11, parallel with the fixed member 10, and arranged on and longitudinally of the top face of the bed 1, and at the rear edge or side of the member 10. The upper portion of the rear side or face of the member 10, is concave or recessed to form one half of the bead forming trough or cylinder *a*, while the front longitudinal side or face of the movable die member 11, is formed by convexing or recessing to register with the correspondingly formed portion of the member 10, and coöperate therewith in forming the complete trough or cylinder *a*. The members 10, and 11 interlock below the trough *a*, to prevent independent or relative vertical movement, and yet so as to permit horizontal movement or adjustment of the member 11, toward and from the member 10. To permit this interlocking of the members 10 and 11, we show the rear face of the member 10, formed with a longitudinal groove or depressed seat 12 receiving the longitudinal rib or projection 13, of the member 11.

The adjustable or movable die member 11, is normally held to the fixed die member 10, by any suitable means. For instance, we show belts 4, arranged transversely of and above the bed 1, and below the shaft 3, and passing loosely and transversely through the movable member 11, and transversely through the fixed member 10, and having their heads at the front edge of the fixed member 10. Wheel nuts 40, are adjustable on the rear threaded ends of these bolts 4, and spacing sleeves 41, are interposed between the nuts 40, and the rear face of the movable member 11 so that the movable member 11, is locked or clamped in operative position with respect to the fixed member 10, by the longitudinally movable sleeves 41, abutting the nuts 40, and the movable die member. It will be readily understood by those skilled in the art, that by unscrewing or loosening the nuts 40, the movable die

member can be moved away from the fixed die member, the movable die member during this movement sliding on the bolts and top face of the bed.

- 5 5, is the removable beader rod or mandrel having the longitudinal groove 50, to receive the edge of the sheet to be beaded. This rod extends longitudinally through the trough *a*, and is movable longitudinally thereinto and 10 therefrom through an end thereof. The extended ends of this beader rod are provided with gears 51, 52, adapted to mesh with the pinions 30, of the drive shaft 3, whereby the beader rod is rotated. The gear 52 is 15 removable to permit insertion of the beader rod in the trough as well as to permit its removal therefrom.

The bead forming trough *a*, has a longitudinal top throat or entrance opening *b*, 20 and this throat is arranged in front of, or to one side of, the longitudinal axis or center line of the trough so that the movable die member 11, is formed with a top overhang 110, above said trough and terminating at said 25 throat *b*, while the fixed die member 10 is formed with a straight vertical wall 111, forming the front longitudinal wall of said throat and extending downwardly a distance into and forming a portion of the 30 front wall of said trough.

In operation, the beader rod is inserted into the forming trough *a*, and the operating shaft 3, is turned to bring the radially projecting stop finger 32, rigid with the left 35 hand pinion 30, opposite the outer side face of the gear 51, so as to hold the beader rod against outward longitudinal movement in the trough while the metal sheet to be operated on is inserted in the beader rod groove 40 50. While the parts are in this adjustment with the beader rod groove open at the top portion of the rod, the operators holding the sheet to be operated on in an upright position insert the lower edge of the sheet into 45 the groove 50, and while the sheet is held in this position the gear 52, is applied to the beader rod and into mesh with the opposing pinion 30. The operators, while holding the sheet to be operated on in the upright position, rotate the drive shaft by means of the 50 crank handles 31, in a direction to turn the edge of the sheet on the beader rod and in the trough counterclockwise Fig. 5, (or clockwise according to the arrangement of 55 Fig. 3. The beader rod is given one complete revolution to form the closed bead on the edge of the sheet, and then the gear 52, is removed from the beader rod so that the beaded edge of the sheet can be slipped 60 longitudinally from the beader rod and trough. In forming the bead, the first portion of the revolution of the beader rod will throw the edge portion of the sheet against the straight flat wall 111 and will bend the 65 sheet to form the inner angular edge of the

bead, that is the portion within the groove 50, whereby the sheet is gripped to or by the beader rod so that the continued movement of the rod will draw the sheet down the straight wall 111, and along the curved 70 inner surface of the trough, turning the sheet metal on the rod to form the complete bead. By forming the trough or cylinder with an entrance throat to one side of the vertical plane of the center or axis of the trough and having a straight guide wall merging gradually and without angles into the curved wall of the trough, in connection with the upwardly curving under face of the overhang 110 we are enabled to operate 75 on comparatively thick or heavy sheet metal, for instance, on metal as heavy as 22 gage, and form beads in one operation. Our device forms the bead "edge" and then turns the metal to form the bead, thereby avoiding the necessity of first forming the "edge" 80 by various devices and then placing the material having the "edge" so formed in a beader to form the bead, as has been generally necessary heretofore when operating 85 on comparatively heavy material.

A bushing of the same contour as the forming trough *a*, but of smaller dimension, can be placed inside the trough or cylinder whenever it is desired to form a bead of a 95 smaller diameter, and it is for this purpose that the movable die member 11, is provided, as it is only necessary to loosen or shift the relative positions of the die members when a bushing is to be placed in or removed from 100 the trough.

The work guiding vertical wall 111, at its lower portion gradually merges into the curved wall of the trough and thereby guides and directs the sheet metal to the beader 105 rod, causing it to adhere or conform thereto and preventing heavy sheet metal from springing away from the surface of said rod, while the overhang 110, not only maintains the beader rod and bead down in 110 proper position in the trough in completing the formation of the bead, but the reduced or upwardly curved or rounded under edge portion of said overhang permits the metal of the completed bead to slightly open or 115 spring from the rod whereby the bead can be slipped longitudinally from the trough and beader rod without removing the beader rod and without releasing or opening the die members.

We employ an actuating shaft provided with pinions and meshing with gear wheels on the beader shaft in order to attain the necessary power for operating on heavy sheet metal, and thereby attain certain material advantages in beading machines designed for operating on heavy material although the machine is also capable of handling light and medium weight material.

It is evident that various changes and 130

modifications might be resorted to without departing from the spirit and scope of our invention and hence we do not wish to limit ourselves to the exact disclosure hereof.

5 What we claim is:—

1. In combination, in a beading machine, a base provided with an upwardly extending longitudinal fixed die member, a movable die member parallel therewith and slidable 10 on the top face of said base toward and from the fixed member and normally fixed with relation thereto, the adjoining vertical faces of said die members having portions overlapping to prevent independent vertical 15 movement of said members, horizontal bolts from said fixed die member passing loosely through said movable die member and sleeves and nuts on said bolts for clamping the movable member to the fixed member 20 to form a bead forming trough, an operating shaft carried by said base and having end gears, a removable beader rod arranged in said trough and having end gears normally in mesh with said shaft gears, one of 25 said beader rod gears being removable, substantially as described.

2. In a beading machine, in combination, a base provided with a fixed die member, a movable die member parallel with said fixed 30 member and movable laterally toward and from the same and normally fixed with respect thereto, means for removably and normally fixing said members together in operative relation, the adjacent longitudinal portions 35 of said members being longitudinally recessed to constitute a bead-forming trough having a contracted tangential entrance throat when said members are secured together in operative relation, one of said 40 members having its said longitudinal recess forming a vertical approximately straight wall constituting one wall of said entrance throat and merging downwardly into a laterally curving wall forming a portion 45 of the curved floor and side surface of said trough, the other member having its said recess transversely curved and forming the remaining portion of the curved floor and opposite side surface of the trough with 50 a longitudinal overhang projecting toward said vertical wall and forming the opposite wall of said throat and at its under surface curved laterally and upwardly in continuation of the curved inner side surface of the 55 trough, and means for drawing the work down said vertical wall and around in said

trough and up under said overhang, substantially as described.

3. A beading machine forming trough provided with a top entrance throat to one side of the longitudinal center of the trough and at the receiving side of the trough having a vertical work-engaging wall at its lower portion gradually merging into the lower portion of the curved wall of the 60 trough, and on the opposite and finishing side of the trough having a permanent top-overhang forming the top curved wall of the trough and at its underside curving upwardly and outwardly in continuation of the 65 interior curved surface of the trough, in combination with a longitudinally-removable beader rod in said trough under said permanent overhang and having end gears at least one of which is removable, and an 70 actuating shaft parallel therewith and having gears in mesh with said beader rod gears, substantially as described.

4. A beading machine forming trough provided with a contracted top entrance 80 throat *b*, to one side of the longitudinal center of the trough having a vertical tangential work guiding wall 111, at the receiving side of the trough and gradually merging into the curved wall of the trough, and with 85 a permanent top overhanging 110, at the finishing side and over the longitudinal center of the trough and fixed with respect to said wall, in combination with a longitudinal-removable beader rod in said trough and 90 under said overhang.

5. In a beading machine, in combination, a base, die members thereon forming a bead forming trough, a longitudinally removable beader rod arranged longitudinally in said 95 trough and provided with end gears, at least one of said gears being removable from said rod, an actuating shaft carried by said base and parallel with said rod and having gears adapted to mesh with the gears of said rod 100 and provided with a radial stop arm projecting from the side face thereof and rigid therewith and adapted to engage the outer face of one of said beader rod gears for the purpose substantially as described. 105

In testimony whereof we affix our signatures, in presence of two witnesses.
